ATTORNEYS.

UNITED STATES PATENT OFFICE.

ANDREW T. HAWLEY, OF ALTON, ILLINOIS.

THRASHING-MACHINE.

SPECIFICATION forming part of Letters Patent No. 293,019, dated February 5, 1884.

Application filed November 1, 1883. (No model.)

To all whom it may concern:

Be it known that I, ANDREW T. HAWLEY, of Alton, Madison county, and State of Illinois, have invented a new and Improved 5 Thrashing-Machine, of which the following is a full, clear, and exact description.

The object of my invention is to provide a new and useful improvement in thrashing-machines, whereby waste of grain is prevented, 10 and the grain is thoroughly separated from the straw.

The invention consists in various parts and details of construction and combinations of the same, as will be fully described and set 15 forth hereinafter.

Reference is to be had to the accompanying drawings, forming a part of this specification, in which similar letters of reference indicate corresponding parts in all the figures.

20 Figure 1 is a longitudinal sectional elevation of a thrashing-machine provided with my improvements, parts being broken out. Fig. 2 is a longitudinal elevation of the heavy beater, parts broken out. Fig. 3 is a cross-sectional elevation of the same on the line *x x*, Fig. 2. Fig. 4 is a longitudinal elevation of the light beater, parts being broken out. Fig. 5 is a cross-sectional elevation of the same on the line *y y*, Fig. 4.

25 The thrashing-cylinder A is journaled at the end of the box, in the usual manner. A short distance within the box a heavy beater, B, is journaled, and a short distance from the same a light beater, C, is journaled, the light beater C being located considerably higher than the heavy beater B. Between the beaters B and C a guard, D, is located, which is inclined downward from the top of the box in the direction from a point above the heavy 30 beater B to a point below the light beater C. The heavy beater B is constructed with four wings formed of boards about seven-eighths of an inch thick, the beater being eleven inches in diameter. The said boards or wings E are 35 attached to a cast-iron head, F, in the manner shown in Figs. 2 and 3, and are covered with heavy sheet-iron, *a*, and are provided with a casting, G, secured on the outer edge, from which casting spikes H project, which are 40 about one inch long and about four inches apart. The spikes are so arranged that those

on one wing set centrally between the spikes on the next wing, or in staggered position lengthwise and circumferentially of the beater. The wings are securely tenoned to the cast 55 heads F. The light beater C is thirteen inches in diameter, and is provided with four wings, J, bolted to a square shaft, K, and braced by braces L. The beater B is revolved in the reverse direction of the thrashing-cylinder A, 60 and the beater C is revolved in the reverse direction of the beater B. The heavy beater B catches the straw from the cylinder A before it has a chance to fall, and throws it into the space above the beater, from which space 65 it has a fall of about twenty-eight inches, the guard or deflector D guiding the straw downward. The smaller beater C, running in the opposite direction of the beater B, strikes the straw while it is falling, and assists the separation of the grain from the straw. The two 70 beaters also prevent the cylinder from throwing the straw over the fingers without being thoroughly handled by the said fingers.

Having thus described my invention, I 75 claim as new and desire to secure by Letters Patent—

1. A thrashing-machine constructed with a heavy beater adjoining the thrashing-cylinder and revolving in an opposite direction thereto, and a light beater adjoining the heavy beater above and in rear of it, and revolving in an opposite direction thereto, whereby the straw will be received from the cylinder by the heavy beater and thrown upward, and as 80 it falls be subjected to the action of the light beater, substantially as herein shown and described.

2. In a thrashing-machine, the combination, with the thrashing-cylinder A, of the heavy 85 beater B, adjoining the cylinder and revolving in a direction opposite thereto, the light beater C adjoining the heavy beater B above and in rear of it, and revolving in an opposite direction thereto, and of the downwardly-inclined 90 guard or deflector D between the beaters B C, whereby the heavy beater B will receive the straw from the cylinder and throw it upward against the deflector, and as it falls be subjected to the action of the light beater, 95 substantially as herein shown and described.

3. In a thrashing-machine, the beater B,

consisting of a central shaft, wings covered with sheet-iron, and a casting, G, having spikes H upon the outer edge of each wing, substantially as herein shown and described.

5. 4. In a thrashing-machine, the combination, with the cylinder A, of the beater B, constructed with four wings covered with sheet-iron, and provided on the edge with castings

having spikes, and of the beater C, provided with four wings suitably braced, substantially as herein shown and described.

ANDREW T. HAWLEY.
